ARCH SUPPORTING SIPHON

Charles Gilbert Hawley, Chicago, Ill., assignor, by
mesne assignments, to Downflow Syphon Company,
Cleveland, Ohio, a corporation of Ohio.

Application April 12, 1937, Serial No. 136,488

3. Claims. (Cl. 122—68)

This invention relates to improvements in and for the water-steaming-and-circulating siphons that occupy longitudinal, vertical positions in locomotive fireboxes and which are called upon 5 to support wholly or in part the refractory brick that compose a fire-box arch. The invention has further and special reference to siphons of the U-shaped "downflow" type described and claimed in my allowed application S. N. 82,953.

10 The invention consists first, in a thermic siphon of U-shaped cross-section and specially formed to aid in the distribution of water within the siphon and to support arch brick upon the exterior of the siphon. And, second, the invention 15 consists in arch brick of special formation, complementary to the described special thermic siphon.

The invention will be readily understood upon reference to the accompanying drawings, which 20 form parts of this specification, and in which: Fig. 1 is a vertical, longitudinal section of a locomotive boiler and firebox constructed and equipped in accordance with this invention; Fig. 2 is a vertical cross-section on the line 2—2 of Fig. 25 1; Fig. 3 is an enlarged cross-sectional detail taken from one of the siphons of Fig. 2, and better illustrating the present invention.

The construction of the exemplary boiler and 30 firebox exhibited here is too well known to require extensive description.

The firebox 2 is of the internal, stayed type 35 common to locomotive boilers. Its fuel door is marked 3 and the fuel bed or fire is marked 4. The gases rise within the box and sweep forward, departing through the flues 5. The thermic 40 siphons, so-called, are marked 6, two being shown. The siphons here exhibited and to which the present invention particularly appertains, are of the "downflow" type that take water from the rear water leg 7 of the boiler and deliver water and steam through the crown sheet 8 and into the steam space S.

These "downflow" siphons are described and 45 claimed in my said application S. N. 82,953, and are more specifically described and claimed in my companion application entitled Downflow siphons, of even date herewith.

Such siphons are thin hollow water walls that 50 divide the upper part of the fire chamber 2 into several parts; and, to increase the flame travel from fuel bed to flues it is common to equip the firebox with an inclined refractory baffle, called an arch. The flame travel is shown by arrows in Fig. 1.

55 The present invention is concerned with a

specifically novel construction and support for that arch; the arch in association with the siphons being broadly claimed in said companion application entitled Downflow siphons.

First to be noted is a cross wall 9, which is 5 lodged within the combustion chamber portion 10 of the firebox. That wall has vertical notches which accommodate the lower, forward parts of the siphons 6. The arch proper extends upwardly and rearwardly from the wall 9 and is composed of specially shaped brick 11 which extend cross-wise of the firebox, from siphon to siphon, and from siphons to firebox side sheets; all finding special supports upon said siphons. Those supports are provided by grooved portions 6' of the 10 siphons, into which the ends of the brick 11 fit, as well shown in Fig. 2 and as fully detailed in 15 Fig. 3.

All brick used in making up the wall 10 and the arch proper are of sizes which permit them to be 20 carried into the firebox through the fuel door 3.

Referring to Fig. 3, it will be seen that the 25 hollow wall or siphon is composed of spaced apart side sheets 6a, which are joined by many short staybolts 12. At the bottom the sheets are joined in the U-shaped section 6b, which forms the closed bottom of the wall or siphon. At that point the sheets 6a are united by a fusion weld 6c. The rear end 6z of each siphon is similarly made. If desired, the entire siphon can be made 30 by folding a single sheet, thereby avoiding the bottom weld 6c, but it is more convenient to make the siphon as here shown.

The upper parts of the sheets 6a and end portions are flared out to form the flanged top, 6d. 35 As is common the flaring top of the siphon is united with the crown sheet 8 by butt welds 8a. The whole crown sheet is supported by crown bolts 13 and certain thereof are fastened in the flanges 6d of the siphon, to more securely support that 40 part with and from the crown sheet.

Special novelty attaches to the grooves 6', which 45 are here provided in the side sheets 6a; and also resides in the restricted longitudinal siphon throat 6x, which is formed by the inwardly extended or grooved parts 6'. Most conveniently, the grooves 6' are formed by pressing or stamping the sheets before they are formed into the siphon body, and those grooves extend longitudinally of the siphon 6, parallel with the bottom of 50 the siphon, as well shown in Fig. 1.

The inclined portion of the brick arch extends 55 only part way toward the rear end of the siphons and the grooves 6' need not be longer than the

arch, though it is admissible to extend the grooves from end to end of the siphon.

Obviously, the lower sides of the grooved portions 6' provide shoulders upon which the ends 5 of the brick 11 may rest; and hereunder each brick 11 is provided with a complementary end rib 11a, preferably extending from end to end of the brick.

The brick 11 occupy inclined transverse positions, as well shown in Fig. 2 and are assembled 10 as there shown. By preference, the free ends of the brick are provided with interlocking parts 11b, to prevent disengagement after the brick are assembled as shown.

15 As explained, the water enters each siphon through its rear end, passing downward along the bottom 6a thereof. During operation water is evaporated very rapidly within the siphon and it is a distinct advantage that the lower part of 20 the siphon is converted into a water conduit leading to the lower corner of the siphon; and, that the constricted longitudinal throat 6x controls the rise of water and steam from the lower part

of the siphon, thus ensuring a good distribution of both throughout the siphon.

Attention is called to the fact that if the siphon is to be made with a longitudinal bottom weld 6c as shown in Fig. 3, it would be better to dispense with the threaded and headed staybolts 12 herein shown and to substitute therefor welded stays, after the manner set forth and claimed in my companion application of this date, entitled Thermic siphons and the like.

I claim:

1. A locomotive firebox siphon comprising a longitudinal water wall having a brick supporting recess or groove formed in its side.

2. The structure as claimed in claim 1, in combination with refractory brick having end ribs, complementary to said groove.

3. The structure as claimed in claim 1 and having one such groove in each of its sides, said grooves being opposite and thus presenting a constricted internal throat, as and for the purpose specified.

CHARLES GILBERT HAWLEY.
